FLOOR FURNACE

Horace J. Smith, Hugo F. Beichel, Arnold D. Smith, and Clyde C. Potter, Los Angeles, Calif., assignors to Ward Heater Co., Ltd., Los Angeles, Calif.

Application April 25, 1933, Serial No. 667,782

8 Claims. (Cl. 126—116)

This invention relates particularly to floor furnaces of the type in which liquid fuel is used as the heating medium. In the embodiment of the invention shown in the accompanying drawings for purposes of explanation, applicants show a type of burner in which one or more annular wicks are used in suitable fuel troughs for starting purposes and in which, when the wicks are lighted, the oil in the troughs begins to vaporize. 5 As this vapor rises between perforated annular shells, air is drawn through the perforations and mixes with the vapor to make a combustible mixture. The burner soon becomes hot enough to gasify the oil in the troughs. The draft created 10 between the shells lifts the flame above the wicks and thereby discontinues their burning.

Although said wicks are used only when starting the burner, it is important to have the same level at all times in order to uniformly heat the 15 burner. These furnaces are usually located beneath the floor and are suspended therefrom.

One of the objects of this invention, therefore, is the provision of means for leveling the burner within the furnace, from the top thereof and 20 without any inconvenience to the operator.

In furnaces of this character the annular shells are supported independently on the fuel troughs and are adapted to be removed therefrom for 25 cleaning purposes. Much difficulty is encountered in replacing such shells in their proper positions, and particularly when the furnace is in an inconvenient location, as it is when under a floor.

It is, therefore, an object of this invention to 30 form a unit of the several shells and make it removable bodily and replaceable at will and in a convenient manner, with guide means for replacement.

A further object of the invention is the provision of means for simultaneously adjusting both 35 the burner and the device for admitting fuel thereto, whereby the relative difference in levels remains constant at all times. A gravity control device is provided for admitting fuel to the burner and is in turn supplied with fuel from an intermediate, float-controlled valve, in the fuel supply line. If the needle valve controlling the flow of fuel into the gravity control device fails to operate to tightly close the inlet, an overflow pipe is provided for directing the fuel into a bucket. When 40 the fuel in the bucket reaches a predetermined level the bucket trips, causing an actuation of certain levers to force the needle into its seat.

It is an object of this invention to provide

means for indicating from a convenient place in the top of the furnace when the bucket has been tripped. It is also an object of the invention to provide means easily accessible to the operator for dumping the bucket containing the liquid fuel and simultaneously setting the gravity-control device for normal operation. 5

Other objects and advantages of this invention will appear from the following description of the invention as here illustrated and which we will 10 now describe in detail. In the drawings

Figure 1 is a vertical sectional view through a floor furnace embodying our invention, with parts shown in elevation;

Figure 2 is a horizontal sectional view taken on 15 the line 2—2 of Fig. 1, with the cover to the furnace removed;

Figure 3 is a sectional view through certain fuel feed control mechanism;

Figure 4 is a cross sectional view taken on the 20 line 4—4 of Fig. 1;

Figure 5 is a vertical, fragmentary sectional view on an enlarged scale, taken on line 5—5 of Fig. 4;

Figure 6 is a similar view taken on the line 6—6 25 of Fig. 4;

Figure 7 is a sectional view taken on the line 7—7 of Fig. 4; and

Figure 8 is a horizontal sectional view taken 30 on line 8—8 of Fig. 3.

Referring now in detail to the drawings, 10 designates the usual floor grate, set in a suitable opening in the floor 11. Suspended from the floor is an outer box or shell 12 of sheet metal, 35 with the usual asbestos or other insulating material 12'. The floor of this outer shell is designated 13, and it has suspended thereunder a smaller box or shell 14, with an opening in its bottom, designated 14', with a screen covering 40 15 therefor, as seen in Fig. 1.

An inner shell or hood 16, is suspended from the floor grate 10, and forms a sort of skirt, spaced inwardly from the outer wall 12, as shown, this space providing passageway for cold air down through the floor grate in the usual manner. 45 The furnace body proper is designated 17, and is of box-like form, open at its bottom and supported through the floor 13, as clearly indicated in Fig. 1, and is provided with a cover 18, with handle 18' for removing the cover. This cover is removed in Fig. 2. From said furnace body 17 are two large pipes or conduits 19 and 20, terminating in a box-like member 21, having two vertical openings 22, 22, therethrough, and an 50 55

- outlet pipe or conduit 23, extended out through the skirt 16 and the shell 12, as seen in Figs. 1 and 2. The smoke or fumes from the furnace body 17 can pass through the two conduits 19 and 20, into the box-like member 21, and out through the pipe 23, without communicating with the vertical openings 22, 22, said openings being walled conduits for circulation of air therethrough to be heated.
- Within the furnace body 17 are shown four concentrically positioned drums or shells, designated 24, 25, 26 and 27, each having openings 24', 25', 26' and 27', through its wall. A top plate 28, adapted to the upper ends of said shells is placed thereupon, said plate having annular depressions, as 28', to fit between adjacent shells, leaving the raised portions to fit down over two adjacent shells, as is clear from Fig. 1, said top plate also having therein circumferentially of extending slots or openings, as 28^a, three of which are shown in Fig. 2, above the annular space formed between shells 26 and 27, while the space between shells 24 and 25 is open around the outer edge of the top plate 28, as at 28^b.
- Said drums or shells 24, 25, 26 and 27 are tied together by means of a through bar 29, inserted through suitable openings in shells 25, 26 and 27, with the outer shell 24 placed thereover and secured thereto by means of screws 30, 30. Said bar 29 has depending therefrom two guide pins 31, 31, again referred to. A central sleeve or tubular member 32 is screwed into said bar at its lower end and at its upper end projects through the top plate 28, with a flange 32' under said top plate, as shown. An upper section 33 is screwed on to the upper end of said member 32, and fits down on the top plate 28, as shown, and through these tubular members 33 and 32 is extended a rod 34 having a T-handle 34' on its upper end, and at its lower end said rod is screwed into a central standard member 35, on which is a plate or table member 36, said standard member 35 being anchored at its lower end in a supporting bracket member 37, supported by means of depending brackets, as 38, four of which are shown attached at their upper ends to the furnace body 17. On the top of the top plate, at one side thereof, is a guide finger 39, again referred to.
- From the description thus far made, it will be seen that by removing the top 18 of the furnace body, and unscrewing the rod 34, by its handle 34', the entire unit consisting of the concentric shells 24, 25, 26 and 27, the central members 33 and 32, the through bar 29 and the depending guide pins 31, 31, can be lifted bodily from the furnace body 17, for cleaning, repair or inspection. Between the lower ends of drums or shells 25 and 26, is placed an inverted channel iron member 40, secured to the through bar 29 by means of screws 41, 41, as seen in Figs. 1, 4 and 6. This member is of annular form and has a series of openings 42 therethrough.
- Supported in the table or plate 36, on the upper end of the standard 35, are two fuel pipes, as 43 and 44, with a cross connecting supply pipe 45, the lower ends of the pipes 43 and 44 being extended downward and closed by means of caps 43' and 44', respectively.
- A fuel trough member 46, of general annular form, and providing two V-shaped fuel troughs 47, 48, with an annular portion 46' therebetween with openings 42' therethrough, is clearly shown in Figs. 4 and 5 and 7. The openings 42' register with the openings 42 in the channel mem-
- ber 40, as will be understood from the showing in Figs. 4 and 5. This fuel trough member 46 is supported on the plate or table 36 by means of spacer members, as 49, held in place by means of screws 50. Mounted in the troughs 47 and 48 are two annular wicks 51 and 52, which set edgewise in the bottoms of said troughs, as shown.
- The fuel flows up through the pipes 43 and 44 and into the troughs 47 and 48, and is picked up by the wicks 51 and 52, ready for ignition from above, through the slots 28^a in the top plate in the usual manner. At the places of connection of the two fuel pipes 43 and 44 with the bottom of the trough member 46, the adjacent wall portions dip to the level of the bottom of said troughs, as at 46^a.
- On the plate or table 36, at the left hand side thereof, is a guide finger 39', adapted to be in alignment with the guide finger 39 on the top plate 28, to facilitate the adjustment of the removable unit when they are put into place.
- Referring to Figs. 2 and 3, the liquid fuel is supplied from any suitable source through a pipe 53, into a float controlled valve 54, from which the fuel flows through a flexible pipe 55, and thence into a reservoir 56, through the bottom thereof, and through the port 58, which is controlled by means of a needle valve or rod 59, also seen in Fig. 2, which is connected to be operated by the float 60, pivoted at 61, in bracket 62, in a well known manner. It will be noted that the sectional view of these parts shown in Fig. 3 is taken on an irregular sectional line shown on Fig. 2, being the line 3—3, and while the parts are small, this mechanism is all old and forms no part of the invention but is shown to show how the invention is applied thereto.
- From the reservoir 56 the liquid fuel is permitted to pass out through a valve mechanism 40 at 63, with outlet port 64, controlled by a valve rod 65 from the floor grate 10. This valve rod 65 is screw threaded in its body 63 and is turned by means of a handle 66, having a pointer 66' moving over an indicating dial 67. This is old, except that applicants have extended the valve rod to the floor grate for convenient operation.
- From the outlet 64 from the reservoir 56, the fuel flows through pipes 45 and thence into pipes 43 and 44 and up into the fuel troughs 47 and 48, in which the wicks 51 and 52 are placed, as before described.
- In the event that the needle valve 59, first referred to, should stick or for some reason fail to fully close the port 58, and the fuel should continue to flow into the reservoir 56 and up around the float 60, it would overflow through a pipe or nipple 68 into a bucket 69 until said bucket was filled sufficiently to overbalance its supporting lever 70, pivotally supported at 71 and 72, as seen in Fig. 2, whereupon said lever 70 is pulled down to the broken line position, indicated in Fig. 3, the inner end of said lever 70 being connected with a coiled spring 73, with a fulcrum connection at 74, the opposite end of said spring being held by means of an adjustable anchorage at 75, whereby said spring functions as a quick acting booster for said lever 70, after it has been moved downward a short distance, this accelerated movement operating to strike the needle valve or rod 59, through a sleeve or collar 76 placed thereon for that purpose. This is designed to force said needle valve into the seat and close the port 58 into the reservoir.
- The bucket 69 can then be tripped from the

floor register by means of a rod 77, provided at its upper end with a finger loop 78, and a spring 79, which is compressed as the bucket descends, pulling the finger loop 78 down into the well 5 or bracket 80, as shown in light broken lines in Fig. 3. When the finger loop is thus down in the dotted line position, it indicates that the bucket has been operated by an overflow of fuel and has descended as a means for forcing the needle 10 valve 59 closed.

In order to return these parts to their normal position, the operator pulls up on the rod 77, which tilts the bucket on the hinge joints at 81 and 82, to empty the same, the overflow fuel 15 being dumped into the ground under the floor. As said bucket is raised in the dumping process, it strikes the lever 76 and returns it to its normal position, as shown in full lines in said Fig. 3. The rod 77 is attached to the bucket by means 20 of a hinged member 83, the free portion of which is provided with a slot 84, through which the rod 77 works, with two confining balls or beads 85 and 86, above and below said member, as shown. These joints are such as to permit the bucket 25 to be turned on its side sufficiently to dump the contents and to permit the operation as described. This convenient means for dumping the bucket and returning the lever to normal position, with the indication of the pull rod 77, constitutes one 30 of the features of applicants' invention.

Referring again to Figs. 1 and 2, we will describe the adjusting means for simultaneously adjusting the burner mechanism and the float controlled mechanism for the purpose of leveling 35 these mechanisms. The supporting bracket at 37, Figs. 1 and 2, it will be seen, is attached to the furnace body by means of supporting brackets 38, 39, heretofore referred to, and these brackets are provided with angle portions 81, 87, to which 40 are attached the adjusting rods 88, 88, having screw threaded connection at their upper ends with depending brackets 89, 89. There are three 45 of these adjusting rods, as will be clear from Fig. 2, the side next to the outlet conduits 19 and 20, being bolted to the furnace body, as at 90, with a slot connection in the body sides 17, as at 90', for original adjustment at the time of installing, the brackets 38, 39, and the body sides 17, 17, being 50 sufficiently flexible laterally to permit leveling by turning the rods 88 slightly, as may be necessary.

The operation of the invention as here shown and described may be briefly described as follows: Assuming that the float controlled valve 54 is 55 full and the supply thereto has been closed, said fuel then flows by gravity to the reservoir 56, through the opening 58 to raise the float 60 and close the needle valve 59. The operator operates the valve rod 65, by means of its indicating handle 66, to admit fuel to the pipes 45, 43 and 44, leading 60 to the burner V-shaped troughs 47 and 48, to feed the wicks for starting purposes. The operator then turns off the same rod 65, and lights the wicks from above, through the slots 28^a as before described and in the usual manner, the cover 18 65 being removed for this purpose. The burning of the wicks develops sufficient heat to vaporize the oil in the troughs. As this vapor rises between the shells 24, 25, 26 and 27, air is drawn through the perforations 24', 25', 26' and 27' to form a 70 combustible mixture which burns with a blue flame. The draft between the shells operates to lift the flame above the wicks and this results in sufficiently heating the shells and the troughs so the fuel is gasified as it enters the burner. When 75 the burner is sufficiently hot, the operator again

turns on the valve rod 65 to permit the continued supply of fuel to the burner troughs. The wicks and the initial supply of fuel are for the purpose of priming or starting the burner, in the usual and well known manner. The operation of the burner 5 is now automatically continued. Should the needle valve 59 get stuck, or leakage occur to cause overflow from the reservoir 56, as before described, the overflow will fill the bucket sufficiently, as before described, to cause it to trip and 10 force the valve closed, thus shutting off the fuel supply and preventing possible fire or other damage.

Thus applicants have provided certain improvements which make it possible to adjust the 15 burner and fuel control mechanism to keep the necessary level condition for the best results, and have also provided means to indicate when the mechanism has clogged or otherwise is not operating properly. Applicants have also provided a 20 structure in which the unit consisting of the annular shells, the through rod 29, and the channel member 40, with the guide rods, can be released and lifted bodily from the fuel trough member 46, the lower edges of said shells fitting said trough 25 member 46 as clearly indicated in the enlarged views in Figs. 5 and 6. In replacing the removable unit, it is only necessary to turn the mechanism until the guide fingers 39 and 39' are in vertical 30 alignment, which insures that the guide rods or pins 31, 31, will enter their openings in the table plate 36. These improvements make for great convenience and saving of time in installing the furnace, or in cleaning or repairing any of the parts thereof, or for renewing the wicks when 35 needed.

We do not limit our invention to the showing made, except as we may be limited to what is claimed in the accompanying claims.

We claim:

1. In a floor furnace, in combination with a floor grate and the enclosing housing therefor, of a furnace body within said housing, concentrically spaced shells within said furnace body forming concentric annular spaces therein, means securing said shells together as a unit for bodily removal from said furnace body, an annular burner member within said furnace body providing concentric fuel troughs for liquid fuel and adapted to interfit with the lower ends of said shells, 50 means for feeding liquid fuel to said troughs, means for adjusting said burner member for leveling purposes, annular wicks in said fuel troughs, a removable cover for said furnace body, and means for lifting said assembled shells as a unit 55 from said burner member and said furnace body.

2. In a floor furnace, a floor grate, a furnace body suspended thereunder, a plurality of concentrically arranged shells therein providing concentric annular spaces therebetween, said shells 60 having means securing them together as a unit, a burner member of annular form within said furnace body and adapted to interfit the lower ends of said shells and to detachably support the same, means for feeding liquid fuel to said burner member, wick means in said burner member for starting purposes, means operable from the floor grate for adjusting said burner member for leveling purposes, and means for automatically feeding liquid fuel to said burner member, said means 65 being mounted thereon and adjustable therewith.

3. In a floor furnace, in combination, a floor grate, a furnace body suspended thereunder, a burner member of annular form within said furnace body and having therein concentrically ar-

- ranged fuel troughs, annular wicks therein, means for automatically supplying liquid fuel to said fuel troughs, said burner member and said fuel feed being adjustable for leveling purposes, means 5 operable from the floor grate for leveling said burner member, a series of concentrically arranged shells within said furnace body upon said burner member spaced to form annular spaces therebetween, means securing said shells together 10 in spaced relationship as a unit, said shells interfitting at their lower ends with said burner member, means detachably holding said shell unit on said burner member, whereby said shell unit can be bodily removed from said burner, guide means 15 for replacing said shell unit upon said burner member, and means for lifting said shell unit bodily from said furnace body.
4. In a floor furnace of the character shown and described, a plurality of concentrically 20 spaced shells forming annular combustion chambers therebetween with openings through their walls, a top plate covering said shells with openings therethrough registering with said spaces, means securing said shells together in spaced relationship, said securing means having guide means thereon for replacing said shell assembly as a unit in operating position, and an annular burner member formed to detachably interfit with the lower ends of said shells and having 25 fuel troughs formed therein, a furnace body enclosing said shell unit and said burner member, and means for lifting said shell unit bodily from said furnace body, with means extended through said shell unit for releasably securing it in place 30 on said burner member.
5. In a floor furnace, in combination, a floor 35 grate, a furnace housing thereunder, a burner member in said housing having means to receive liquid fuel therein, wick means therein, means forming mixing and combustion chambers above said burner member, means for automatically supplying liquid fuel to said burner member, said means including a float controlled valve and reservoir, a movably mounted receptacle, 40 means for directing overflow of liquid fuel from said reservoir to said receptacle, whereby a predetermined amount of overflow fuel in said receptacle moves said receptacle and forces said float controlled valve closed, means for emptying 45 said overflow receptacle, and at the floor grate 50 means for indicating that the overflow receptacle has been moved.
6. In a floor furnace, in combination, a floor 5 grate, a furnace housing thereunder, a burner for liquid fuel in said housing, a float-controlled valve for controlling flow of fuel to said burner, an overflow receptacle movably supported to receive overflow liquid fuel, said receptacle being connected to move with a predetermined weight of liquid therein and close said valve, means 10 visible at the floor grate for indicating when said receptacle has moved, said means being operable manually for emptying said receptacle, the movement of said receptacle under said predetermined weight operating to cut off fuel supply to 15 said burner.
7. In combination, a floor grate, a furnace, a burner member adapted to receive and hold liquid fuel, a reservoir for fuel with float controlled valve for controlling the inflow of fuel 20 to said reservoir, valve means for controlling flow of fuel to said burner, a receptacle to receive overflow fuel from said reservoir, said receptacle being movably mounted, means operable by the movement of said receptacle for closing said 25 float controlled valve, means visible at said grate for indicating when said receptacle has moved, said last means being operable manually for emptying said receptacle and returning said receptacle to its normal position. 30
8. In combination with a furnace having a burner member adapted to hold liquid fuel, a reservoir for supplying fuel thereto, a float controlled valve for controlling the inflow of fuel to said reservoir, a manually operable valve for 35 controlling flow of fuel from said reservoir to said burner, a movably supported receptacle positioned to receive overflow fuel from said reservoir when the control valve sticks, means whereby the movement of said receptacle closes said 40 valve and cuts off said fuel supply, and means visible and operable from above for emptying said receptacle and returning it to its normal position, said last means indicating that said receptacle has been moved. 45
